UNITED STATES PATENT OFFICE.

ALLAN H. BACON, OF WEBSTER GROVES, MISSOURI.

ELECTRO-THERAPEUTIC TOOL-HOLDER.

SPECIFICATION forming part of Letters Patent No. 394,807, dated December 18, 1888.

Application filed November 5, 1888. Serial No. 290,050. (No model.)

To all whom it may concern:

Be it known that I, ALLAN H. BACON, of Webster Groves, Missouri, have made a new and useful Improvement in Electrical Appliances, of which the following is a full, clear, and exact description.

The improvement is adaptable to a variety of tools having handles and designed for manual use.

10 It consists, mainly, in incorporating in a tool-handle an electric battery having conductors leading therefrom and so disposed about the handle and provided with such electrodes as to enable an electric current to be transmitted through the hand while manipulating the tool.

The improvement is illustrated in connection with a pen or pencil holder, to which instrument it is especially suited.

20 In the annexed drawings, making part of this specification, Figure 1 is a view in perspective exemplifying the use of the improved holder; Fig. 2, a side elevation of the holder; Fig. 3, a longitudinal section of the holder; Fig. 4, a cross-section on the line 4 4 of Fig. 2, and Fig. 5 a cross-section on the line 5 5 of Fig. 2. The last two views are upon an enlarged scale.

25 The same letters of reference applied to the several drawings denote the same parts.

The pen-holder A is of any of the usual constructions, saving as it may be modified or supplemented by the improvement in question. The "case," "handle," or "holder" a, as it may 35 indifferently be called, is adapted at one end to receive and hold a pen, a', pencil, or other article to be held, and at the other end it may be finished in any suitable manner. In the present instance the holder is provided with 40 a cap, a², or other removable part suitable for closing the chamber a³, formed within the holder for the reception of the battery B, used for generating the electric current.

I desire not to be restricted to any special 45 battery or means for producing the electric current; but a desirable battery is shown. It is substantially such an one as is employed in electric belts, being composed of cells b b, suitably united by means of the connection b', 50 and having suitable conductors, b² b³, leading, respectively, from the ends of the battery. The conductors in turn lead to electrodes C C',

which are of suitable material for conducting the electric current, and are so located upon or in the holder as to enable the hand D, 55 broken lines, Fig. 1, of the person using the holder to readily come in contact with them. To this end the electrodes and the conductors may be variously disposed about the holder; but, to enable the current to be transmitted 60 through the thumb d and forefinger d' of the hand, the electrodes are arranged upon opposite sides of the holder, substantially as shown, and the conductors b² b³ lead to them, as follows: The conductor b² leads from the innermost cell, b, outward through the shell of the holder to the electrode C, and the conductor b³ leads from the outermost cell, c, outward 65 through the holder-shell to its outer surface, and thence along the holder and to the electrode C'. The electric current is transmitted whenever the hand is in contact with either 70 the two electrodes or the conductors, or with one of the electrodes and the conductor leading to the other of the electrodes. The 75 electrodes can be variously shaped and variously arranged, as stated, and when with them arranged as shown the conductors may lead in various ways to them. I consider, however, a desirable arrangement is exhibited. 80 The electrodes are countersunk in the surface of the holder, as well as that part of the conductor b³ which appears upon the outer side of the holder, as thereby no undesirable projection is formed upon the holder. 85

When it is desired to dispense with the electric current, the holder can be turned around, so that the hand in grasping it shall not form a contact with the electrodes, and to this end there are spaces a⁴ a⁴ upon the holder between 90 the electrodes, and the pen or pencil or other article may be so connected with the holder that in inserting it in the holder it can be turned around therein to conform to the position of the hand upon the holder. 95

In other forms of tools the electrodes are located to suit the position of the hand when applied to the tool.

When the battery is of the kind shown, it is adapted to be treated in the usual manner for 100 renewing its strength. By employing a tight partition, as at a⁵, Fig. 3, or otherwise making the chamber a³ practically tight, the acid liquid used in renewing the battery can be ap-

plied (after removing the cap a^2) to the battery while within the holder.

I claim—

- 5 1. A tool-holder having means, substantially as described, for generating an electric current, and conductors leading therefrom to that part of the holder which is grasped by the operator's hand, substantially as described.
- 10 2. The combination of the holder, means, substantially as described, for generating an electric current, conductors, and electrodes, said electrodes being spaced upon the holder to enable the hand to be applied either to the

electrodes or elsewhere, substantially as described.

15 3. The combination of the holder, chambered as described, the pen, the cap, the battery, the conductors, and the electrodes, substantially as described.

20 Witness my hand this 31st day of October, 1888.

ALLAN H. BACON.
